John Gorham's, Design for Spoons.

Design #699

Patented April 10, 1855.

Fig. 1.

Fig. 2.

John Gorham of Providence R. I.
Letters Patent No 699 Dated April 10. 1855

The schedule referred to in these Letters Patent and making part of the same.

To all whom it may concern

Be it known that I, John Gorham, of Providence, in the County of Providence and State of Rhode Island, have invented or produced a new and original design for spoons, and I do hereby declare that the following is a full and exact description of the same, reference being had to the annexed drawings making a part of this specification, in which

Fig. 1. is a front or face view of a spoon and,
Fig. 2. is a back view of do, showing my new and original design.

A. represents the bowl of the spoon and B. the handle. The top or outer part of the handle has an ornament (a) upon it on its front side, see fig. 1. and also an ornament (b) just below the ornament (a). The edges of the handle have a bead (c), at each side & these beads are connected at the top or outer part by a scroll (d) between the two ornaments (a), (b.) the lower ends of the beads (c) terminate each in scrolls or rounded ends (e), at their junction with the bowl A.

The back side of the handle B, see fig. 2, has a bead (f) at its edges, of the same form as the bead (c) on the front side. The lower ends of the beads (f) terminate in scrolls or rounded ends (g) at their junction with the bowl, the same as on the front side, and their upper or outer ends are connected by a scroll (h) similar

Des. 699

to that on the front side.

Above the scroll (h) there is an ornament (i) similar to the ornament (a), on the front side.

On the back of the bowl (h), and adjoining the scrolls or rounded ends (g) of the beads (f) there is an ornament (j), made in relief on the bowl. Said Ornament (j) extending nearly to the centre of the back of the bowl as clearly shown in the drawing.

I claim the ornaments (a), (b), (i), (j), and the beads (c), (f), with their scrolls (d), (e), (g), (h), when the whole are arranged to form a new and ornamental design for a spoon as herein shown and described.
